UNITED STATES PATENT OFFICE.

RALPH C. STIEFEL, OF ELLWOOD CITY, PENNSYLVANIA.

TUBE-FORMING MILL.

Application filed April 5, 1926. Serial No. 99,777.

The invention relates to the general type of tube-forming mills in which a heated pierced billet or other tubular blank is intermittently acted upon increment-by-increment to elongate it and reduce its wall thickness, the blank being mounted upon a mandrel which is intermittently moved into and through the mill to present successive increments of the blank to the action of the mill, and the invention has particularly to do with mills of this type in which successive increments of a blank are acted upon by a series of uniformly grooved rolls which have orbital movements about central axes.

15 The object of the invention is to improve the construction and operation of mills of the type described.

The invention is illustrated in the accompanying drawings, of which Fig. 1 is a vertical central sectional view through a mill in the plane of its working pass, this plane being indicated by the line I—I, Fig. 2; Fig. 2 a vertical central sectional view of the mill taken at right angles to Fig. 1, the plane of view being indicated by the line II—II, Fig. 1; Fig. 3 a detail vertical sectional view taken on the line III—III, Fig. 2; Fig. 4 a detail sectional view taken on the line IV—IV, Fig. 3; Fig. 5 a horizontal sectional view taken on the line V—V, Fig. 2; and Fig. 6 a view corresponding to Fig. 5 illustrating a modification of the mounting of tube-forming rolls.

The mill provided according to this invention comprises a pair of driven shafts rotatably mounted in a suitable housing, around each of which there is arranged a series of grooved forming rolls held in spaced relation to each other. Each of the several grooved rolls forming this series has a peripheral portion in bearing contact with a cylindrical face of the shaft around which the rolls are disposed, the arrangement being such that the shafts rotate the grooved rolls in a manner similar to the action of a planetary gear. Provision is made for causing the two series of grooved rolls to move at uniform angular rates about the axes of the shafts upon which they bear so that the rolls forming the two series cooperate in pairs to act upon successive increments of a tubular blank. The mill is intended to be used in coordination with a suitable feeding mechanism adapted to intermittently advance a mandrel and its supported blank between the functioning of each pair of grooved rolls to

present successive increments of the blank to the successive pairs of acting rolls, the feeding mechanism being also adapted to rotate the blank on its longitudinal axis through an angle of 90° between the action of successive pairs of grooved rolls, this turning being effected at the same time the blank is moved forwardly. Because such blank-feeding mechanism is well known in this art, and because various forms of it may be used in coordination with the mill provided according to this invention, no such feeding mechanism is illustrated in the drawings.

Having reference now to the illustrative embodiment of the invention, a pair of shafts indicated as a whole by the letters A and B are suitably supported by a housing 1, the lower shaft B preferably having no provision for vertical movement, and the upper shaft A being mounted for a limited vertical movement, the extent of which may be determined by screws 2. Since both of these shafts are preferably constructed alike, and are so shown in the drawings, the explanation of their construction will be limited to a description of shaft A. Adjacent to its ends it is provided with bearing portions 3 which are rotatably mounted on bearing blocks 4, and at its ends it is provided with angular portions 5 for connection to wabblers or other suitable drives. Adjacent to bearing portions 3, this shaft is provided with shoulders 6 surrounding which there is a cage 7 for supporting the ends of a series of grooved tube-forming rolls 8, the cage being rotatable upon the shoulders, but, for a reason presently to be explained, preferably having friction bearing contact with the shoulders. The central portion 9 of shaft A is cylindrical and affords a bearing for peripheral portions of the grooved rolls.

As shown in Fig. 4, cage 7 may comprise a pair of rings 10, one surrounding each of the shoulders 6 of shaft A, each of which rings is provided with a series of inwardly extending arms 15 arranged between rolls 8 and meeting each other at the center of the mill as indicated at 16, these two parts of the cage being connected to each other by rods 17 extending through arms 15. Each roll 8 is preferably provided at its center with a groove and preferably has two cylindrical portions adjoining the groove bearing upon the central cylindrical portion 9 of shaft A. The ends of each roll 8 are provided with trunnions 18 rotatably mounted

in bearing blocks 19 supported for movements radially of shaft A in suitable radially disposed pockets formed on the inner or adjacent faces of the rings 10 of cage 7.

5 Provision is made for continuously holding the peripheral bearing portions of grooved rolls 8 in contact with the cylindrical portions 9 of shaft A. To such end, the peripheries of cage rings 10 are preferably 10 provided with a plurality of arc-shaped springs 25 each having its ends yieldingly bearing upon the outer faces of an adjacent pair of bearing blocks 19 to urge them toward shaft A. These springs may be attached to cage 7 by suitable bolts 26. Provision is also made for causing cage 7 to rotate with shaft A at such times as the grooved rolls may not be acting upon a blank. This may be done in whole or in 15 part by the frictional contact of the inner bearing surfaces of cage rings 10 upon shaft shoulders 6. In addition to this, friction rings 27 may be arranged between the inner faces of cage rings 10 and off-set portions of 20 shaft A, the friction rings being provided with projections 28 which engage the cage rings. These friction rings are yieldingly pressed into engagement with shaft A by means of a plurality of springs 29 so that 25 additional force is applied to cause the cage to rotate with the shaft when pairs of rolls 8 are not in engagement with a blank.

Surrounding shaft B there is a cage 7^a which supports a series of grooved rolls 8^a, 35 the construction and arrangement of this cage and rollers being the same as the corresponding parts surrounding shaft A. To the end that the several rolls 8 and 8^a forming the two series may be brought into tube-forming positions in pairs, cages 7 and 7^a 40 are caused to move at uniform angular rates about the axis of their contained shafts by providing the peripheries of these cages with intermeshing teeth 30 and 30^a.

45 In the embodiment of the invention illustrated in Figs. 1-5 forming rolls 8 and 8^a are arranged with their axes parallel to each other and to the axes of shafts A and B. If desired, the forming rolls may be mounted 50 to form pairs of cross-rolls. In other words, they may be so supported in their cages that their axes cross each other when they meet in pairs in tube-forming or reducing positions. To this end, as shown in Fig. 6, rolls 55 surrounding shaft A may have their trunnions 36 mounted in oblique openings 37 in bearing blocks 38 supported by a cage 39, and the second series of rolls 40 surrounding shaft B may be similarly mounted in a cage 60 41, the axes of the rolls crossing each other as shown. By so mounting the two series of forming rolls, a tubular blank being acted upon by the rolls is turned on its longitudinal axis by the cross roll action of the rolls.

65 In the operation of the mill, having refer-

ence particularly to the embodiment of the invention illustrated in Figs. 1-5, a tubular blank 45 is supported upon a mandrel rod 46, which, by any suitable form of feeding mechanism, is intermittently advanced to 70 present successive increments of the blank to the action of cooperating pairs of forming rolls 8 and 8^a, and is turned on its longitudinal axis through an angle of 90° between the operation of each pair of forming rolls. 75 Shafts A and B are suitably driven in the directions indicated in Fig. 1 by the arrows placed on these shafts with the result that rolls 8 and 8^a are caused to roll upon blank 45 in the directions indicated by the arrows 80 on the pair of these rolls shown in Fig. 1 as being in contact with the blank. The rotation of the successive pairs of cooperating rolls 8 and 8^a causes the cages to rotate in the same directions as shafts A and B, as is 85 indicated by the arrows extending through the rolls 8 and 8^a shown in Fig. 1 as being in contact with the blank. The intermittent rolling action of the pairs of rolls 8 and 8^a serves to reduce the wall thickness of the 90 blank and to elongate it as generally indicated. Pressure is imparted to the blank through the forming rolls by the peripheral bearing of the forming rolls upon shafts A and B which hold the forming rolls in 95 definite spaced relationship to each other so that the reduction and elongation of the blank is uniform throughout. During the interval elapsing between the operation of successive series of forming rolls, cages 7 100 and 7^a are rotated to present a succeeding pair of forming rolls to the blank both by the friction of cage rings 10 on shaft shoulders 6 and by the friction drive imparted to the cages by the shafts through friction 105 rings 27. After the tube has been reduced and elongated, such irregularities as may appear on its outer surface, and as usually appear on tubes formed by mills of this type, may be removed in the well known manner 110 by passing the tube through a reeling mill.

According to the provisions of the patent statutes, I have explained the principle and operation of my invention, and have illustrated and described what I now consider 115 to represent its best embodiment. However, I desire to have it understood that, within the scope of the appended claims, the invention may be practiced by other forms of mills than that particularly illustrated and 120 described.

I claim as my invention:

1. A seamless tube-forming mill, comprising a pair of rotary shafts, a series of grooved forming rolls held in spaced relation to each other around and having peripheral portions in bearing contact with a cylindrical face of each of said shafts for imparting rotation to the rolls, and means for causing said two series of rolls to con- 125

tinuously move at uniform angular rates about the axes of the shafts upon which they bear.

2. A seamless tube-forming mill, comprising a pair of driven rotary shafts, a roll-supporting cage mounted for rotation upon each shaft, a series of grooved forming rolls rotatably mounted in each cage in spaced relation to each other, to operate in pairs and having peripheral portions in bearing contact with a cylindrical face of the shaft within the cage, and means for causing the cages to continuously move at uniform angular rates about the axes of their respective supporting shafts.

3. A seamless tube-forming mill, comprising a pair of driven rotary shafts, a roll-supporting cage mounted for rotation upon each shaft, a series of grooved forming rolls rotatably mounted in each cage in spaced relation to each other, yielding means for

holding peripheral portions of said rolls in bearing contact with a cylindrical face of the shaft within the cage, and means for causing the cages to continuously move at uniform angular rates about the axes of their respective supporting shafts.

4. A seamless tube-forming mill, comprising a pair of driven rotary shafts, a roll-supporting cage mounted for rotation upon each shaft, a series of grooved forming rolls rotatably mounted in bearings arranged in each cage for movements radially of its contained shaft, means acting through said bearings for holding peripheral portions of said rolls in bearing contact with a cylindrical face of said shaft within the cage, and means for causing the cages to continuously move at uniform angular rates about the axes of their respective supporting shafts.

In testimony whereof, I sign my name.
RALPH C. STIEFEL.
